UNITED STATES PATENT OFFICE.

BRUCE A. MIDDLEMISS, OF CHUQUQUI CAMATA, CHILE, ASSIGNOR TO CHILE EXPLORATION COMPANY, OF NEW YORK, N. Y., A CORPORATION OF NEW YORK.

EXCAVATING MACHINERY.

1,405,796.

Specification of Letters Patent.

Patented Feb. 7, 1922.

Application filed May 10, 1920. Serial No. 380,066.

To all whom it may concern:

Be it known that I, BRUCE A. MIDDLEMISS, a citizen of the United States, residing at Chuququi camata, Chile, South America, have invented certain new and useful Improvements in Excavating Machinery; and I do hereby declare the following to be a full, clear, and exact description of the invention, such as will enable others skilled in the art to which it appertains to make and use the same.

This invention relates to excavating machinery designed for open workings, but applicable to mines and the like, and as well to sub-aqueous work.

One object of this invention is to provide an excavator of large capacity in which there shall be no swinging of the boom or corresponding part after the shovel has been filled with material, thus saving the time consumed by apparatus of this sort in swinging the shovel from loading position to unloading position and back again, which is recognized by shovel operators as consuming about 75% of the time. Another object is to provide an easy and graduated discharge from the shovel into the car, scow, or corresponding dump, and associated with this advantage is that of providing a single discharge orifice under which the dump shall be located and avoid the necessary changes in position of the car into which the material is dumped.

A still further advantage is the economy in operating power whereby reason of the avoidance of the excessive power incident to the swinging action in handling immense quantities of material in the dipper, there is simply necessary the power to raise the dipper and load vertically. For instance, where the usual machines of today have as a maximum about twelve tons handled in each shovelful, the present mechanism is capable of taking care of and discharging without damage to the dump a load of 20 cubic yards to the shovel, or thirty-five tons.

Another advantage is that by the construction present in this apparatus there is a considerable saving in damages to the loaded vehicle. For instance, it is not uncommon in swinging large booms and shovels for the car to be struck sidewise and tipped from the track. In the use of this invention the contents of the dipper are dis-

charged from substantially an overhead position and out of a chute with no side thrust on the car. In connection with the side swinging of the handle to load and unload there is a very severe stress upon the mechanism at the inner end of the handle which is frequently dislocated and fractured, for the weight of the shovel, with or without load, acting through the leverage of the handle presents a force to be resisted which is almost insurmountable. Again, in digging, careless shovel men will start to swing the load before the dipper is entirely out of the bank and thus introduce a tremendous stress upon the boom construction at the handle end. The manifest advantage of avoiding these circumstances by the construction of this invention is a very important one.

Other advantages will become apparent in connection with the following description of the drawings forming a part of this specification; in which—

Fig. 1 shows an elevational view partly in section with a dipper at work in a plane transverse to the tracks on which the excavator is positioned;

Fig. 2 is a plan view of the excavator shown in the same position;

Fig. 3 is a rear elevation of the excavator;

Fig. 4 is a plan view of the dipper and portions of its handle and chute;

Fig. 5 is a side elevation of the dipper and a portion of its handle;

Fig. 6 is a detailed sectional view on the line 6—6 of Fig. 7, and shows the means for mounting and manipulating the inner end of the handle;

Fig. 7 is a detailed elevational view of a portion of the boom adjacent the inner end of the handle;

Fig. 8 is a diagrammatic plan view of the operating mechanism for turning the excavator, for raising the boom and manipulating the dipper; and

Fig. 9 is an elevational view of the rear of the operating mechanism of Fig. 8, showing the arrangement of the operating mechanism in diagrammatic form, and also showing the side longitudinal view of the truck with a diagrammatic showing of the motive power for propelling the excavator.

In the drawings 10 represents a double rail track upon which the excavator may

travel. 11 represents a track for the receiving car 12 of any desired gauge. The excavator is mounted upon a steel frame body 15 provided with double wheeled trucks 16, and the body is elevated to permit the passage thereunder of receiving vehicles 12, by means of raised pillars 17 to permit the passage of loading vehicles. An operator's cab 18 is located upon one side of the body and provides the necessary outlook upon the tracks 10 and 11, and contains control devices for the motor mechanism 19 connected by sprocket chain or other suitable driving means 20 with the driving gears on the trucks 16. The body 15 and its supporting pillars 17 are constructed of suitable steel shapes and plates, and it has an upper floor 25 and a ceiling 26 therebelow supporting the motors 19 and the appurtenant parts. Extending between the floor 25 and the ceiling 26 is a circular hopper 27 in the form of an inverted frustum of a cone, which in addition to its soft steel surface plates has lining plates 28 of manganese steel or other similar wear resisting material arranged as parts of its conical surface. The hopper 27 is located at the center of the carriage 15. In order to prevent direct falling of large rocks into the dump, a stationary buffer 31 having a supporting frame work 32 and a wear resisting cover plate 33 of manganese steel, or the like, is suitably positioned at the upper entrance to the hopper. A supplemental swinging buffer 34 having a support 35 on each side thereof is located above the stationary buffer 32 so as to slow up the descending material and reduce the shock on buffer 31 and the car below. A cover plate 36 of manganese steel is formed to the shape of the buffer and replaceably attached thereto. In order to enclose the buffers and prevent dust from passing to the interior of the cab a hood extends along the sides of the hopper and from the floor of the cab to the roof thereof and encloses the discharge space. A turn table 37 is carried above the floor 25 of the body and is turned on double flanged rollers 38 running on a track 39 upon the floor 25, and motive power is applied to the turn table by means of a large exterior gear 40 actuated in a manner to be later described. In order to maintain the turntable and the cab at the axis of the gear 40, inner and outer thrust rings 22 and 23 are provided. The ring 22 depends from the floor of the cab 41, and the ring 23 is connected with the floor 25 of the body 15. The top of the hopper has a flared guard ring 14, which supports the edge of the chute 56, and the thrust rings are outside of this ring 14. The turn table 37 carries a cab 41 in which are the controls for the apparatus.

65 Turn table 37 forms a foundation member

with incident heavy construction, supporting as it does the cab and machinery, the stiff legs 45 and the A frame 46, the boom 47, the shovel 48 and the shovel handle 49, together with the safety cables 50 and the boom hoisting cables and apparatus 51. Other parts not specifically mentioned are likewise carried by the turn table, all forming a considerable weight and requiring a staunch construction to be made of shapes and plates, the design of which need not be elaborated upon.

As substantially the usual practice is employed in the stiff legs, the A frame, the safety cables and the boom hoisting apparatus, it is undesirable to describe them in detail, as they are carried in the usual mountings joined to the turn table or their connected parts in a well known manner. The boom 47 is connected to the turn table which carries the boom base member 52 into which enters the pivot member 53 whereby the thrust plate 54 and the base plate 52 are pivotally connected. The thrust plate 54 extends across the end of the boom which is formed at each side of two box girders 55 of suitable steel construction separated from each other a substantial distance, and carrying therebetween and pivotally attached thereto a chute 56. The box frame members 55 at their upper ends have an elbow 57 serving to render rigid the box girders at their upper and reduced ends, and also withdrawing the upper ends from the bank to be removed.

100 The box girders carry bearings for a shaft 58, and this shaft has secured thereto two sets of sheaves 59 and 60. The outer sheaves 59 have winding thereon cables connected at their other ends with winding mechanisms, and the sheaves 60 are connected by cables directly to the dipper. The cables extending to the winding mechanism and those extending to the dipper are wound in opposite directions, and it will be evident that by varying the relative size of the sheaves, a variation in relative speed between the movement of the cables may be obtained.

105 Intermediate the foundation plate 52 and the elbow 57 is located a second shaft 61 extending across the lower edge of box girders 55 of the boom 47, which may be termed the handle manipulating shaft.

110 Shaft 61 and its mountings and adjacent parts are shown in detail in Figs. 6 and 7. 120 Bearing members 62 which are supported by extensions 63 secured to the vertical sides of the boom members 55 have alined bearings for receiving the shaft 61. Spanner nuts retain the shaft in the bearing member 62. 125 Intermediate the bearings 62 on each side of the boom gears 64 are interposed, the same being fast to the shaft 61 by means of keys 65. Gears 64 are shown with an insert 70 of wear resisting material such as manga- 130

nese steel to suitably take care of the heavy service required at that place. It is manifest, however, that these gears might be easily made of solid manganese steel castings and serve the same purpose. The gear inserts 70 co-act with corresponding gear inserts 71, on a rack 72 carried by a hydraulic cylinder 73, which will be later described in detail. The power transmitted to the gear 10 64 is carried to a similar gear 74 also keyed to shaft 61 and having similar inserts 70 which in turn co-act with gear inserts 71 upon a rack 75 fastened on the bottom of each side of the dipper handle 49. The power 15 of the gear 74 is thus transmitted to the rack 75 and manipulation thereof up and down and in and out is thus secured.

The handle of the dipper to which the racks 75 are connected is constructed as 20 shown in cross section in Fig. 6, of a lower plate 76 extending between two side members 77 which are built up of a thick metal plate 78, a stick of timber 79 and a thick top plate 80 forming a trough like member which carries a wear resisting inner lining 81 or chute 25 formed of a section which extends upon both inner sides of the handle and across the bottom. These may be made of wear resisting material being suitably fastened to the other 30 parts of the dipper handle, it being understood, of course, that aside from the member 81 each side of the dipper handle is a duplicate of the other.

The upper plate 80 has a longitudinally 35 extending rib 82 on its upper face, of a length corresponding to that of the rack 75. Grooved pulleys 83 are carried by substantially triangular saddle members 86, which are arranged at opposite sides of the dipper 40 handle, between the gears 74 and the adjacent bearing 62. The saddle members carry bolts 84 upon which the pulleys 83 are arranged, the bolts being held in place by nuts 85. Each of the saddle members has a bearing 45 upon the shaft 61, and referring to Figure 6 it will be seen that the said members have lateral flanges extending above the pulleys 83. The purpose of the saddle members is to align the dipper handle and maintain 50 the racks 75 in contact with the gears 74.

The bearing members 62 are extended downwardly along the lower surface of the boom 47 and carry on each side a pivot member 190 which serves to support the upper 55 end of the chute 56, the lower end of which rests upon the upper edge of the hopper guard ring 14, and slides thereupon depending upon the movement of the boom 47 when it is lowered after cessation of the digging 60 operations for any length of time. The lower chute 56 has an outer trough made up of steel plates and shapes connected to which in section is the inner manganese sheet chute similar to chute 81 of the dipper 65 handle. These parts are not shown in detail

as it is thought unnecessary to do so, as the construction of the lower chute is plain from the foregoing consideration of the chute formed in the dipper handle. If desired the construction of the lower chute may be 70 altered as necessary.

The dipper handle substantially as described extends outwardly to dipper 48, where as shown in Figs. 4 and 5 connection is made with the two side castings 90 which 75 are securely bolted to the contiguous end portions of the dipper handle. As shown in Fig. 6 the sides 90 are ribbed for the sake of rigidity and their forward portions are joined again to the digging edge 91 of the 80 dipper which carries upon its edge reversible teeth 92, both parts obviously being of wear resisting material and likewise built for rigidity. The bottom of the dipper is formed by a heavy casting 93 suitably connected at the inner end to the dipper handle, at its edges to the sides 90 and at the front to the dipper front 91. It should be noted that the bottom 93 is positioned at an angle to the bottom surface of the chute 81. Fas- 85 tened upon the dipper front are the bail connections 94 supplied on each side of the dipper and apertured at 95 to receive a connecting pin joining a bail 96 thereto. Connected to bail 96 is an equalizer 97 necessary 90 on account of the use of double cables 98 which extend from the equalizer to the inner sheaves 60 at the head of the boom. The cable 98 is flat and the upper end is fastened to the bottom of the slot in sheaves 60 and coils 100 thereon between the sides 66 on said sheaves. As before stated, the sheaves 59 and 60 are rigid with the shaft 58, and the said sheaves have marginal flanges 66 and 159, respectively. The cables 98 wind upon the sheaves 105 59, and other cables 99 wind upon the sheaves 60, but in the opposite direction to the cables 98. The arrangement is such that when the cables 99 are unwound, the cables 98 are wound up, and it will be noticed that the sheaves 60 are of greater diameter than the sheaves 59, so that the cables 98 move faster in winding and unwinding than the cables 99. The cables 99 are flat corresponding to cables 98, there being four of them instead 110 of two of the latter and they extend to a guide sheave or pulley 100 positioned in a pillow block 101 located at the upper surface of the boom 47 at or adjacent to the elbow 57. From the pulley 100 the cables 99 extend to the cab or house and to sheaves there- 115 in actuated in the manner described later.

The inner end of the dipper handle 49 receives its manipulation or driving by means of movement of the sliding cylinders 73 on each side of the boom sliding upon a stationary piston 105 connected to a hollow piston rod 106 passing through a stuffing box 107 in each end of said cylinder, extending as it does upon both sides of the piston. The 120 125 130

interior of the piston rod while hollow for most of its length is plugged when the piston is fastened thereto, there being connections on each side of the plug with the respective sides of the piston to slide the cylinder in one direction or the other depending upon the position of the proper control valve in the operator's cab. The hollow piston rod is piped to the accumulator 122 by the pipe 102 through a set of jointed short pipes 103 from which connection is made directly to the boom end of the piston and through the pipe 104 to the upper end of the piston rod. The valve controlling the flow to one or the other ends of the piston rod is located in the jointed pipe 103 and operated from the control head 123 in the operator's cab 124. The cylinder carries on its top a fixed bearing edge 108 in contact with the guide pulleys 109 having rims 110 and carried upon shaft 111 supported at its ends in bearings 112 fast to a transverse member 113 within the boom, there being a plurality of pulleys 109 positioned throughout the extent of the guide bar 108 so as to suitably guide the cylinder in its travel. In order to support the cylinder 73 from below there is positioned on the lower edge of the boom members 55 a short shaft 114 upon which turn pinions 115 having teeth the size of those on the rack 72 and co-acting therewith so as to form a carrying means for said cylinder. As the cylinder 73 may be traveled along the boom for some distance pinions 115 are distributed from very near the lower end of the boom upwardly to some distance above the inner end of the dipper handle 49. Of course, other means may be provided for actuating the inner end of the handle, it being intended to describe only one method therefor.

It should be noted that when the dipper 48 is in the dot and dash line position of Fig. 1 or adjacent thereto, after the dipper has been raised a short distance, the handle 49 and its chute 81 form in effect the back edge of the dipper, at least serve to retain the material therein in the lowermost position while when the dipper is in the full line position the dipper becomes a portion of the chute, the material sliding along the bottom thereof which is in reality an extension of the chute proper. Because of the fact that the dipper and its controlling mechanism is mounted on a turn table, it will be obvious that the dipper may be swung to work ahead of the track 10, or at either side thereof, swinging through an angle of more than 180°. Thus the excavator can clear a foundation for its track and swing to either side of the track, meanwhile depositing the excavated material in the dump car in the same manner as that shown in the position of the machinery in Fig. 1.

Reference to Fig. 2 will show that the

upper end of the lower chute 56 is wider 65 than the lower end, and the width is such as to receive upon and within the upper end the inner end of the chute 81. Consequently when the handle and the dipper are raised to an angle of 30° to the horizontal a gradual discharge of the dry material from the dipper 48 will occur, and therefrom into the chute 56 during the continuation of the movements of the dipper and handle into their uppermost position which is about 45° 70 to the horizontal. Of course, if desired the handle may be halted in any desired intermediate position so as to graduate the discharge into the lower chute 56, and thus shocks upon the lower part of the excavator and 80 the dump car are avoided. It will be noted that this operation starts, continues and finishes all in the same plane, which is that of the boom 47, and that there is no time consumed in the swinging of the boom and the 85 dipper.

The power plant located in the cab 41 will now be described, although it forms no part of the present invention and its inclusion is simply necessary to describe one means of 90 actuating the cables 51, 98 and 99, and also for turning the turn table, and as well supply fluid under pressure for the cylinder 73. The power plant comprises a hydraulic electric installation in which there are duplicate 95 sets of power units comprising motor 120 and two pumps 121 which supply water or other fluid to the accumulator 122 up to a defined pressure, after which the pumps simply churn the water, one motor turning continuously while in use and a valve or valves being manipulated from a control head 123 in the operator's cab 124 located midway on one side of the cab, the valve serving to connect the accumulator with the desired hydraulic cylinder. At each side of the cab are hydraulic cylinders 125 fixed in position and carrying a plunger 126 joined to a cross head 127 carrying thereon a set of sheaves 128 around which a cable 129 passes. Slides 130 for the cross head 127 are provided. The cable 129 passes between sheaves 128 on each side of the cab around guide sheaves 131 and 132 and from thence to sheaves 133 around which there are a plurality of cables, and 110 above which is a turn table operating gear 40 contacting with and driving the circular gear 21 on the turn table. The piston 126 of the respective cylinders move in the opposite direction so that upon the outer movement of one, the cable 129 shall be traveled in one direction and drive the gear 40 and the circular gear 21 in one direction, whereas upon the reverse the turn table and gear 21 are driven in the opposite direction to swing 115 the turn table and cab. At the end of the movement of the turn table locking means 120 act to retain it and connected parts in a fixed

position so that no movement thereof shall later ensue. The movement of the cross head 127 is utilized in raising the boom when for any reason digging operations are to be suspended and it is not desirable to retain the boom in operative position. The cables 51 for hoisting the boom extend between a set of sheaves 43 and corresponding sets of sheaves on the plate 44 at the top of the A frame. The cable finally is led from the sheaves 43 over the sheaves 68 and from there downwardly to a drum 69 from which they are led to the cross head 127, and the power is thus supplied to the boom hoisting cables upon the movement of the plunger 126, the cable 129 being disconnected for the time being. Once the boom has been raised to position the safety cables 50 are fastened at their respective ends at the head of the boom 47 and the plate 44 and the cables 51 disconnected and stowed away in a convenient manner.

A similar installation is employed for the actuation of the boom cables 99. A pair of cylinders 140 operated by a valve similar to that already mentioned carry plungers 141 which have mounted at their outer ends a cross head 142 carrying sheaves 143 around which the cable 99 passes after being fastened at the end to the foundation of the cylinder 140. Cross heads slides 144 are provided upon which cross heads 140 move. Upon the outward movement of the plungers 141 the sheaves 143 are caused to travel with their cross heads and thus exert a pull upon the cables 99 which pass over guide pulleys 145 to the guide pulley 100, and from thence to the inner sheaves 59, the outer end of the dipper cables being fast to sheaves 60 coiling thereupon between the sides in the manner described.

Reference to Figs. 8 and 9 will show for the most part the mechanism above described, and there is also included the boom cylinder 73 and its piping to which water under pressure from the accumulator is admitted upon manipulation of the valve in the dipper operator's cab 124. The tanks 150 piped to the accumulator 122 supply the water lost by leakage, and also serve as settling tanks for the discharged water from the hydraulic cylinders described, and permit the air introduced to the water in the hydraulic cylinders to disengage itself from the water before being used again.

In order to counterbalance the weight of the boom, the dipper, and other heavy parts, counterbalance boxes 151 are provided under the floor of the cab, and may be filled 80 with pig iron or other suitable material.

The operation of the excavator comprises at the initiation of operations the movement of the body and the parts carried thereby along the track under the control of

a switch in the operating head in the cab, 65 causing the motor to function and drive the truck. Thereafter, when the boom has been erected and fastened the dipper is driven downwardly into the bank by manipulation of the boom cylinder, which acting upon the 70 rack from the control head in the shovel man's cab, the bottom of the dipper handle controls the elevation of the inner end of the handle. In conjunction with the manipulation of the inner end of the handle 75 the cable from the boom head to the dipper is hauled up by the man in the cab controlling the hydraulic pressure from the control head in the cab. It is apparent that the dipper and the dipper handle are 80 manipulated jointly until the dipper is clear of the bank, at which time the inner end of the dipper handle should be positioned so that the inner end of the chute therein shall sufficiently overlap the lower chute extending to the hopper. After this position is obtained the discharge of the dipper is 85 accomplished by simply continuing the lifting action of the cable until the dipper handle is about 30° to the horizontal. The 90 speed of discharge from this point may be controlled by the rate of lifting of the dipper, as usually when once started it will continue and may be controlled to a nicety by the gradual raising of the dipper. A 95 sudden discharge may also be obtained by the rapid hoisting of the dipper.

Before the dipper has reached its highest position the contents will be discharged in most cases, at which time the descent of the 100 dipper will be permitted and the co-related manipulation of the handle be started. The discharged material when all out of the dipper handle chute is continued into and through the lower chute against the swinging buffer being diverted thereby, so that a comparatively gentle stream of excavated material passes through the chute and down through the hopper into the dump. Large rocks are prevented from 110 dropping from the end of the chute into the dump by reason of the fixed buffer which holds them and passes them to the sides of the hopper, from which place they are dropped with a reduced force, and after 115 permitting a large portion of loose excavated material to fall into the dump capable of absorbing a large portion of the shock which would otherwise occur by direct contact with the interior of the dump.

While the preferred embodiment of the invention has been described hereinabove and illustrated in the drawings as aforesaid, no limitation to the precise structure comprised in such disclosure is contemplated, except in so far as may necessarily be imposed by the language of the appended claims, since the invention is obviously 120 125

susceptible of considerable modification and change within the scope of said claims, and since parts of the invention as disclosed may be employed without others, and in 5 other and different environments.

I claim:

1. In an excavator, a body, a turn table carried thereby, a hopper, a boom, backlegs therefor, connections therebetween, a chute 10 carried by said boom and directing its contents to the above named hopper, a dipper handle mounted in said boom and on the boom and relatively fixed with respect to the boom for moving said handle with respect to said means and the boom, a chute carried by said handle and discharging its contents into the chute carried by the boom, a dipper on said handle manipulated by connections with said boom and loading and 20 discharging into the chute in the handle.

2. In an excavator, a boom, a handle having a dipper supported by the boom, the handle forming a discharge chute for the dipper, and means on the boom and relatively fixed with respect thereto and engaging the handle for moving said handle with respect to said means and the boom.

3. In an excavator, a boom, a hopper at the inner end of the boom, a handle having 30 a dipper supported by the boom, the handle forming a discharge chute for the dipper, a guide chute supported by the boom and delivering to the hopper, the handle delivering to the chute, and means on the boom 35 and fixed relatively to the boom for moving said handle with respect to said means and the boom.

4. In an excavator, a boom, a handle having a dipper supported by the boom, the 40 handle forming a discharge chute for the dipper, and means on the boom and relatively fixed with respect thereto and engaging the handle for moving said handle with respect to said means and the boom, a plurality of rigidly connected reels supported by the boom, flexible members connected with the dipper and winding on sundry of the reels, other flexible members winding on others of the reels in the 45 opposite direction to the first named members whereby when said members are moved in one direction the first named members will be moved in the opposite direction.

5. In an excavator, a boom, a hopper at 55 the inner end of the boom, a handle having a dipper supported by the boom, the handle forming a discharge chute for the dipper, a guide chute supported by the boom and delivering to the hopper, the handle 60 delivering to the chute, and means on the boom and fixed relatively to the boom for moving said handle with respect to said means and the boom, said means comprising racks rigid with the handle, pinions on

the boom, and fluid pressure controlled 65 means for moving the racks.

6. In an excavator, a boom, a hopper at the inner end of the boom, a handle having a dipper supported by the boom, the handle forming a discharge chute for the dipper, a 70 guide chute supported by the boom and delivering to the hopper, the handle delivering to the chute, means on the boom and fixed relatively to the boom for moving said handle with respect to said means and the 75 boom, and a turn table supporting the boom and rotatable about the hopper.

7. In an excavator, a wheeled supporting carriage, a turn table mounted to rotate on the carriage, a boom on the turn table, a 80 hopper at the axis of the table, a guide chute supported by the boom and delivering to the hopper, a handle supported by the boom and having a dipper and forming a discharge chute for the dipper and delivering 85 to the guide chute, means on the boom and relatively fixed with respect thereto and engaging the handle to move the same with respect to the boom, a fixed buffer at the opposite side of the hopper from the chute 90 and a swinging buffer arranged between the fixed buffer and the guide chute.

8. In an excavator, a boom, a hopper at the foot of the boom, a handle supported by the boom and having a dipper at the outer 95 end thereof, and forming a discharge chute for the dipper, a guide chute supported by the boom to which the handle delivers and delivering to the hopper, and means on the boom and relatively fixed with respect 100 thereto and engaging the handle for moving the handle to force the dipper into the ground.

9. In an excavator, a boom, a hopper at the foot of the boom, a handle supported by 105 the boom and having a dipper at the outer end thereof, and forming a discharge chute for the dipper, a guide chute supported by the boom to which the handle delivers and delivering to the hopper, and means on the 110 boom and relatively fixed with respect thereto and engaging the handle for moving the handle to force the dipper into the ground, a turn table rotatable with respect to the hopper on which the boom is mounted, 115 sheaves having guided movement on the turn table, flexible members connected with the boom and with the turn table and passing over the sheaves, and fluid pressure controlled means for moving the sheaves to 120 raise and lower the boom.

10. In an excavator, a boom, a dipper handle, a dipper thereon, connections between the boom and the handle for manipulating the handle and the dipper, a chute on 125 said handle receiving the contents of the dipper, a chute on the boom receiving the discharge from the first named chute, and

bumpers interposed in the path of the material passing along said chutes, one of which is movable to a plurality of positions.

11. In an excavator, a body, a hopper, a bumper adjacent thereto, a dipper, connections between the dipper and the hopper, said bumper directing the discharge of large masses of material directly to the hopper and lessening the force of discharge through the hopper.

12. In an excavator, a body, a hopper, a boom, a dipper, a dipper handle, means in the boom and the dipper handle joining the hopper to the dipper, and means adjacent thereto and contacting with the contents thereof.

13. In an excavator, a body, a hopper, a boom, a dipper, a dipper handle, means in the boom and the dipper handle joining the hopper to the dipper, and means adjacent thereto and contacting with the contents thereof, and retarding the progress of the contents.

14. In an excavator, a dipper having a handle forming a chute through which the dipper discharges, a hopper into which the chute discharges, and a bumper between the

chute and the hopper and adjustable toward and from the chute whereby to close or open the same, and to regulate the discharge from the chute into the hopper.

15. In an excavator, a hopper, a dipper having a handle forming a chute delivering to the hopper, means for operating the dipper, and bumpers interposed in the path of the material passing along the chute, one of said bumpers being adjustable for the purpose specified.

16. In an excavator, a dipper having a handle forming a chute through which the dipper discharges, means for operating the dipper, a hopper to which the handle delivers, a fixed bumper opposite the delivery end of the chute and supported to move with the dipper when said dipper swings in the horizontal plane whereby to retain its position opposite the delivery end of the chute, and a movable bumper between the chute and the fixed bumper and adjustable with respect to the chute to close or open the same, and to graduate the discharge therefrom.

In testimony whereof I affix my signature.

BRUCE A. MIDDLEMISS.
